LADY'S STOCKING

Walter Mueller, Clifton, N. J.

Application February 12, 1951, Serial No. 14,184

Term of patent 14 years

(Cl. D47—7)

To all whom it may concern:

Be it known that I, Walter Mueller, a citizen of the United States, residing at Clifton, in the county of Passaic and State of New Jersey, have invented a new, original, and ornamental Design for a Lady's Stocking, of which the following is a specification, reference being had to the accompanying drawing, forming part thereof, wherein:

The opposite side of the stocking is substantially identical with the side depicted in Figure 1. The essential features of the design reside in the portions shown in full lines on the drawing.

I claim:

The ornamental design for a lady's stocking, substantially as shown and described.

WALTER MUELLER.
